(57) **CLAIM**

I claim the ornamental design for a storage stationary box, as shown and described.

DESCRIPTION

FIG. 1 is a perspective view of a storage stationary box in a closed position.

FIG. 2 is a top view of the storage stationary box.

FIG. 3 is a right side view of the storage stationary box.

FIG. 4 is a left side view of the storage stationary box.

FIG. 5 is a back view of the storage stationary box.

FIG. 6 is a bottom view of the storage stationary box.

FIG. 7 is a front view of the storage stationary box.

FIG. 8 is a perspective view of the storage stationary box in an open position.

FIG. 9 is a top view of the storage stationary box in an open position.

FIG. 10 is a right side view of the storage stationary box in an open position.

FIG. 11 is a left side view of the storage stationary box in an open position.

FIG. 12 is a back view of the storage stationary box in an open position.

FIG. 13 is a bottom view of the storage stationary box in an open position; and,

FIG. 14 is a front view of the storage stationary box in an open position.

1 Claim, 14 Drawing Sheets
